COMPRESSOR

Keith H. Rhodes, Racine, Wis., assignor to Walker Manufacturing Company, Racine, Wis., a corporation of Delaware

Filed July 9, 1962, Ser. No. 208,386
3 Claims. (Cl. 230—139)

This invention relates generally to compressors, and more particularly to a novel vacuum operated air compressor of relatively simple and economical construction.

Commercially available air compressors are generally driven by an external prime mover, for example, an electric motor, internal combustion engine, etc. Such known air compressors generally comprise a number of close tolerance components and therefore inherently necessitate a high degree of care in manufacture and assembly. As a result, the real cost of such known air compressors reflects relative high manufacturing costs as well as a relatively expensive prime mover.

The present invention is directed to a novel air compressor that can be produced at a minimum cost, and which includes an integral prime mover. Both the compressor and prime mover consist of relatively inexpensive stampings, commercially available tubing and plastic sheet material that is cut to specific configurations.

Accordingly, one object of the present invention is an improved compressor.

Another object is a vacuum operated air compressor.

Another object is an air compressor having an integral prime mover.

Other advantages of the instant invention will be apparent from the following specification, claims and drawings, wherein:

FIGURE 1 is a sectional view taken through the compressor of the instant invention;

FIGURE 2 is a cross-sectional view taken substantially along the line 2—2 of FIGURE 1;

FIGURE 3 is a cross-sectional view taken substantially along the line 3—3 of FIGURE 2; and

FIGURE 4 is an exploded perspective view of the internal components of the air compressor with the housing thereof removed.

An air compressor 10, in accordance with an exemplary constructed embodiment of the instant invention, comprises a motor section 11 and a compressor section 12. The compressor section 12 comprises a tubular compressor housing 13 made from, for example, 16-gauge steel tubing. One end portion 14 of the compressor housing 13 is secured to a bearing retainer 16, comprising a pair of juxtaposed cup members 17 and 18, as by brazing.

An inner compressor disc 20 is positioned axially of the housing 12 against the retainer 16. The disc 20 is made from, for example, nylon sheet material cut to a generally circular configuration complementary to the compressor housing 12 and is retained therein in substantially sealed relationship.

The disc 20 has an air inlet aperture 22 (FIGURES 3 and 4) therein that communicates with an air inlet chamber 24 between the bearing retainer 16 and the disc 20. Air entering through the inlet aperture 22 in the disc 20, thence into a compression chamber 28 internally of the compressor housing 12. The disc 20 also has a circular aperture 30 therein for the acceptance of a drive shaft 32 from the vacuum motor section 11, as will be described.

A compressor rotor 40 made from, for example, aluminum bar stock, has a central bore 42 therein for the acceptance of the drive shaft 32 from the vacuum motor section 11. The rotor 40 is rotatable with the shaft 32, torque being transmitted thereto as by a pair of conventional keys 44 and 46.

2

As best seen in FIGURE 2, the rotor 40 has three generally radially directed longitudinally extending slots 50, 52 and 54 for the acceptance of a like plurality of vanes 56, 58 and 60, respectively. The vanes 56, 58 and 60 are made from, for example, nylon sheet stock and are slidable within the slots 50, 52 and 54, respectively. The vanes 56, 58 and 60 move radially outwardly of the slots 50, 52 and 54 in the rotor 40, due to centrifugal force upon rotation, outer edge portions 62, 64 and 66 of the vanes 56, 58 and 60, respectively, slidably engaging an inner peripheral surface 70 of the compressor housing 13 thereby to help define the compression chamber 28. The vanes 56, 58 and 60 are biased radially inwardly of the housing 13 due to engagement with the inner peripheral surface 70 thereof upon rotation.

An outer compressor disc 80 made from, for example, nylon sheet material, is held in juxtaposed relation against an outer end portion 82 of the rotor 40 by an end cap 83 thereby to function as an end wall for the compression chamber 28. The outer compressor disc 80 has a discharge aperture 84 (FIGURES 2 and 3) therein that communicates with a discharge chamber 85 and a discharge nipple 86 on the outer end cap 83. The end cap 83 has an annular rib 90 therein that bears against and positions the outer disc 80 axially of the compressor housing 13. The end cap 83 is secured to the housing 13 as by a press fit.

A drive pin 90 extends through complementary aligned apertures 92 and 94 in the end cap 83 and disc 80, respectively, to position the disc 80 within the compressor housing 13 and preclude rotation thereof. It is to be noted that an inner end portion 96 of the drive pin 90 extends into the central bore 42 in the rotor 40 to avoid interference therewith.

The vacuum motor section 11 comprises a tubular housing 100 made from, for example, 16-gauge steel tubing.

A motor end cap 104 has an annular rib 106 therein that positions an outer motor disc 108 axially of the motor housing 100. The disc 108 is made from, for example, nylon sheet material cut to a circular configuration complementary to the housing 100. The disc 108 has an air discharge aperture 110 (FIGURES 3 and 4) therein that communicates with a vacuum chamber 112 between the end cap 104 and the disc 108. An air pressure depression produced by, for example, the intake manifold of an internal combustion engine (not shown) communicates with the chamber 112 through suitable tubing (not shown) that is secured to a nipple 120 in the end cap 104. A drive pin 122 extends through aligned apertures 124 and 126 in the cap 104 and disc 108 to preclude rotation of the disc 108.

A working chamber 130 is defined internally of the housing 100 and has a vacuum motor rotor 150 therein made from, for example, aluminum bar stock. The rotor 150 has a central bore 152 therein for the acceptance of the drive shaft 32. Rotation of the rotor 150 is transmitted to the drive shaft 30 as by a pair of conventional keys 154 and 156.

The rotor 150 has three generally radially directed longitudinally extending slots 160, 162 and 164 (FIGURE 4), for the acceptance of a like plurality of vanes 166, 168 and 170, respectively. The vanes 166, 168 and 170 are made from, for example, nylon and are slidably radially outwardly of the slots 160, 162 and 164, respectively, due to centrifugal force. Outer edge portions 172, 174 and 176 of the vanes 166, 168 and 170, respectively, slidably engage an inner peripheral surface 180 (FIGURE 1) of the vacuum motor housing 100.

An inner motor disc 200 made from, for example, nylon sheet stock, is juxtaposed against the cup member

18 of the bearing retainer 16 to function as an end wall for the vacuum motor 11. The disc 200 has an inlet aperture 202 (FIGURE 4) therein that communicates with the inlet chamber 24 and the working chamber 130 in the motor section 11.

As noted hereinbefore, the bearing retainer 16 comprises a pair of complementary generally cup shaped stampings 17 and 18 having aligned apertures 220, 222 and 224 therein to facilitate the flow of air within the chamber 24. The member 17 has an annular lip 230 that is accepted in the aperture 30 in the disc 20, and the member 18 has an annular lip 232 that is accepted in a complementary aperture 234 in the disc 200, thereby to position the discs 20 and 200, respectively, and effect a seal between the retainer 16 and the discs 20 and 200.

An annular spacer member 240 is disposed between the members 17 and 18 for the retention of a pair of ball bearings 242 and 246. The bearings are spaced axially of one another to journal the drive shaft 32 which transmits rotation of the rotor 150 of the vacuum motor 11 to the rotor 40 of the compressor 12.

As best seen in FIGURE 3, the end cap 104, motor housing 100, retainer 16, compressor housing 13 and end cap 83 are retained in fixed relationship by a pair of retainer rods 250 and 252 that extend longitudinally of the compressor section 12 and motor section 11.

From the foregoing description, it should be apparent that the air compressor of the instant invention is made up from relatively simple components that can be manufactured without emphasizing close tolerances. The compressor section comprises a simple tubular housing having nylon discs at opposite ends thereof to define a compression chamber. The discs are stamped from nylon sheet stock to a configuration complementary to the housing and with appropriate inlet and outlet apertures. The compressor rotor is fabricated from aluminum bar stock with longitudinal slots therein for the acceptance of a plurality of radially slidable vanes. The vanes are made from nylon sheet stock.

An integral vacuum motor section is constructed in a manner similar to the compressor section and effects drive of the compressor through a self contained drive shaft. The drive shaft is journaled by a relatively simple bearing retainer.

It should be apparent that only a vacuum line need be connected to the vacuum motor section of the compressor to effect energization of the air compressor.

It is to be understood that the specific construction of the improved air compressor herein disclosed and described is presented for the purpose of explanation and illustration and is not intended to indicate the limitations of the invention, the scope of which is defined by the following claims.

What is claimed is:

1. An air compressor having an integral vacuum driven prime mover comprising
  - a pair of axially aligned cylindrical housings,
  - a pair of end caps at opposite ends of said housings, respectively,
  - a bearing retainer between said housings,
  - a bearing in said bearing retainer having
    - a central axis radially spaced from the central axis of said housings,
    - a drive shaft journaled in said bearing and extending into said housings,
    - an inlet disc in one of said housings adjacent said bearing retainer having
      - an inlet aperture therein,
      - an outlet disc adjacent the end cap at the end of said one housing having
        - an outlet aperture therein,
        - a generally cylindrical compressor rotor between said inlet and outlet discs drivably keyed to said drive shaft so as to be rotatable about an axis extending generally parallel to the central axis of said housings

ings in radially spaced relation thereto, said compressor rotor having

a plurality of generally axially extending radially directed slots,

5 a plurality of generally radially slidable vanes in the slots in said compressor rotor, said vanes slidably engaging the inner peripheral surface of said one housing and said inlet and outlet discs to define a variable volume chamber for the compression of air therein upon rotation of said compressor rotor relative to said one housing,

an inner disc in the other of said housings adjacent said bearing retainer having

an inlet aperture therein,

an outer disc adjacent the end cap of said other housing having

an outlet aperture therein,

a generally cylindrical vacuum motor rotor between said inner and outer discs having

a central bore therein for the acceptance of said drive shaft so as to be rotatable coaxially with

said compressor rotor, said motor rotor having a plurality of generally axially extending radially directed slots, and

a plurality of generally radially slidable vanes in the slots in said motor rotor, said vanes slidably engaging the inner peripheral surface of said other housing and said inner and outer discs to define a variable volume vacuum chamber whereby rotation of said motor rotor relative to said other housing effects concomitant rotation of said compressor rotor.

2. An air compressor having an integral vacuum driven prime mover comprising

a pair of axially aligned cylindrical housings,

a bearing retainer between said housings,

a bearing in said bearing retainer having

a central axis radially spaced from the central axis of said housings,

a drive shaft journaled in said bearing and extending into said housings,

a plastic inlet disc at one end of one of said housings adjacent said bearing retainer having

an inlet aperture therein,

a plastic outlet disc at the other end of said one housing having

an outlet aperture therein,

a generally cylindrical compressor rotor between said inlet and outlet discs drivably keyed to said drive shaft so as to be rotatable about an axis extending generally parallel to the central axis of said housings in radially spaced relation thereto, said compressor rotor having

a plurality of generally axially extending radially directed slots,

a plurality of generally radially slidable plastic vanes in the slots in said compressor rotor, respectively, said vanes slidably engaging the inner peripheral surface of said one housing and said inlet and outlet discs to define a variable volume chamber for the compression of air therein upon rotation of said compressor rotor relative to said one housing,

a plastic inner disc in the other of said housings adjacent said bearing retainer having

an inlet aperture therein,

a plastic outer disc at the other end of said other housing having an outlet aperture therein,

a generally cylindrical vacuum motor rotor between said inner and outer discs having

a central bore therein for the acceptance of said drive shaft so as to be rotatable coaxially with

said compressor rotor, said motor rotor having a plurality of generally axially extending radially directed slots,

a plurality of generally radially slidable plastic vanes

in the slots in said motor rotor, respectively, said vanes slidably engaging the inner peripheral surface of said other housing and said inner and outer discs to define a variable volume vacuum chamber, and means for connecting said vacuum chamber to an air pressure depression whereby rotation of said motor rotor relative to said other housing effects concomitant rotation of said compressor rotor.

3. An air compressor having an integral vacuum motor drive comprising

- a pair of axially aligned cylindrical housings,
- a bearing retainer between said housings,
- a bearing in said bearing retainer having
- a central axis radially spaced from the central axis of said housings,
- a drive shaft journaled in said bearing and extending into said housings,
- a plastic inlet disc at one end of one of said housings adjacent said bearing retainer having
- an inlet aperture therein,
- a plastic outlet disc at the other end of said one housing having
- an outlet aperture therein circumferentially spaced from the inlet aperture in said inlet disc,
- a generally cylindrical compressor rotor between said inlet and outlet discs drivably keyed to said drive shaft so as to be rotatable about the axis thereof,
- said compressor rotor having
- a plurality of generally axially extending radially directed slots,
- a plurality of generally radially slidable plastic vanes in the slots in said compressor rotor, respectively, said vanes slidably engaging the inner peripheral sur-

10

face of said one housing and said inlet and outlet discs to define a variable volume chamber for the compression of air therein upon rotation of said compressor rotor relative to said one housing, a plastic inner disc in the other of said housings adjacent said bearing retainer having

    an inlet aperture therein,

a plastic outer disc at the other end of said other housing having

    an outlet aperture therein circumferentially spaced from the inlet aperture in said inner disc,

a generally cylindrical vacuum motor rotor between said inner and outer discs having

    a central bore therein for the acceptance of said drive shaft so as to be rotatable coaxially with said compressor rotor, said motor rotor having

    a plurality of generally axially extending radially directed slots,

a plurality of generally radially slidable plastic vanes in the slots in said motor rotor, respectively, said vanes slidably engaging the inner peripheral surface of said other housing and said inner and outer discs to define a variable volume vacuum chamber, and means for connecting said vacuum chamber to an air pressure depression whereby rotation of said motor rotor relative to said other housing effects concomitant rotation of said compressor rotor.
